PASTER FOR CIGAR MACHINES

Henry H. Wheeler, Brooklyn, N. Y., assignor to
 International Cigar Machinery Company, a
 corporation of New Jersey

Application February 25, 1938, Serial No. 192,458

20 Claims. (Cl. 131—21)

This invention relates to cigar machines, and more particularly to pasters for cigar rolling machines, its object being to provide an automatically controlled precision device with completely enclosed and readily demountable paste-carrying parts insuring cleanliness and high efficiency of operation, being designed for delivering a definite predetermined amount of paste upon a tobacco leaf at the proper moment in each cycle of the machine, provided there is a leaf present to receive the paste.

There are two operations in a cigar machine which require the application of paste: the rolling of the filler charge in the binder leaf, and the winding of the wrapper leaf around the cigar bunch. In the former operation, the binder leaf is held by suction upon a perforated apron stretched over the suction chamber of a suitably shaped rolling table. In this case, the paste must be applied from above by a movable arm, so as to clear the path for the next binder after the paste has been delivered. In the wrapping operation, the wrapper leaf is held affixed by suction to the wrapper carrier which halts for a moment on its way to the wrapping device to receive the paste, hence the latter is usually applied to the wrapper from below at the fixed dwell position of the carrier, preferably in the shape of a loop following the contour of the flag end of the wrapper.

To meet these differing conditions, the design of the improved paster is carried out both for upward delivery of a paste loop from a fixed position, and for downward delivery of a paste spray by a nozzle moved to and from the delivery position at each application.

It is an additional object of this invention to provide an improved pasting mechanism for applying paste to wrappers and binders in which the paste reservoir and the paste conveying duct associated therewith are easily removable from the cigar machine upon which they are located for cleaning, interchange of parts and repairs.

It is a further object of the invention to provide means for building up pressure in the paste reservoir at the start of operations in order to force paste into the paste line whenever the mechanical paste feeding means is not in operation. This structure may assume the form of a priming pump suitably mounted on the paste reservoir.

It is an added object of the invention to provide a paste applying mechanism for applying paste to wrappers and/or binders in which the

paste can be applied gradually or abruptly according to predetermined necessity.

It is a further object of the invention to provide a mechanism for applying adhesive to a cigar wrapper in which simplified means are furnished for elevating the adhesive applying mechanism into contact with the wrapper, and wherein a simplified control mechanism is provided for controlling the flow of the adhesive.

10 The invention also consists in the provision of a novel adhesive applying mechanism wherein the adhesive applying head thereof is moved into adhesive applying position by means other than mechanical, such for instance as hydraulic means, and additional mechanism is provided for controlling the flow of adhesive from said head at the conclusion of its movement to adhesive applying position.

20 The invention also consists in the provision of a novel adhesive applying mechanism having an adhesive applying head, which head is moved by a hydraulic pressure into adhesive applying position, and also in valve mechanism which is hydraulically operated to control the flow of adhesive from said head.

25 With these and other objects not specifically mentioned in view, the invention consists in certain constructions and combinations which will be hereinafter fully described and then particularly pointed out in the claims hereunto appended.

30 In the accompanying drawings which form a part of this specification, and in which like characters of reference indicate the same or like parts:

35 Fig. 1 is a sectional side elevation of the improved paster, arranged for upward delivery of paste to a wrapper held on the wrapper carrier;

40 Fig. 2 is an end elevation partly in cross-section, on line 2—2 of Fig. 1;

45 Fig. 3 is a top view seen from line 3—3 of Fig. 1;

Fig. 4 is a section on line 4—4 of Fig. 1;

Fig. 5 is a section on line 5—5 of Fig. 4;

45 Fig. 6 is an end elevation on line 6—6 of Fig. 1;

Fig. 7 is a top view on line 7—7 of Fig. 6;

Fig. 8 is a top view in enlarged scale on line 8—8 of Fig. 1;

50 Fig. 9 is a sectional end elevation on line 9—9 of Fig. 8;

Fig. 10 is a sectional side elevation of the improved paster, arranged for swingable downward delivery of paste to a binder;

55 Fig. 11 is a top view seen from line 11—11 of Fig. 10.

Fig. 12 is an end elevation showing the paster operating mechanism;

Fig. 13 is a side view of said paster operating mechanism;

Fig. 14 is a sectional side elevation showing a modified form of the improved paster wherein the speed of displacement of the paste is controlled; and

Fig. 15 is an end elevation partly in cross section, on the line 14—14 of Fig. 14.

Referring to Figs. 1, 2 and 3, the housing 12 which is suitably attached to the base 13 of the cigar machine, carries the closed paste reservoir 14, a paste-forwarding plunger 15, and a rock shaft 16 which mounts the automatically controlled operating arm 17. The paste reservoir 14 rests on the top of housing 12 and is secured in place thereon by a spring-tensioned ball 18 fitting into a recess provided in an extension 19 of the reservoir when the latter is pushed into a seat 20 in housing 12 provided for this purpose. Through this construction, when it is desired to remove the reservoir for refilling or cleaning, it is only necessary to apply a horizontal pull to the paste reservoir to remove it from its supports in housing 12, after the paste-delivering parts have been disconnected from their support 50. See Fig. 1.

The paste reservoir 14 at its bottom has a bushed horizontal outlet or bore 21 in which the plunger 15 reciprocates through the medium of lever 17, as shown by dotted lines 15' in Fig. 1. In the wrapper paster, lever 17 is attached by a ball-and-socket joint 22 to a connecting rod 23 which in turn is affixed (see Figures 1 and 2) by a ball-and-socket joint 24 to a cam lever 25 held by a spring 26 against the surface of a cam of the cigar machine similar to that shown in Figs. 12 and 13. At the proper moment in every cycle of the machine, cam lever 25 moves arm 17 into dotted position 17' (Fig. 1) against an adjustable stop-screw 27 in housing 12. This screw has a grooved head with which engages a locking spring 28, and serves to adjust the stroke of plunger 15 which governs the quantity of paste delivered. As shown, the plunger 15 has secured thereto a rectangular collar 29 slidable on guide surfaces provided in housing 12. A spring 30 coiled about plunger 15 bears against housing 12 and collar 29 and thereby normally tends to urge the plunger forward to paste feeding position. The forked ends of arm 17 bear against collar 29 on each side of plunger 15 and hold the latter in non-active position against the pressure of spring 30 as long as the cam lever 25 is inactive.

In the rest position of plunger 15, as shown in Figs. 1 and 10, the collar 29 engages with a depression formed in each of two bell-crank latch levers 301 and 31 fulcrumed on a shaft 32, supported in housing 12, and held in upward tension by stops 33 pressed against them by springs bearing against adjustable sockets 34 by means of which the tension applied to latch levers 301 and 31 is controlled. The lever 301 is connected by a rod 35 with a piston 36 closing a chamber 37 in housing 12, this chamber communicating by a pipe 38 with the suction system of the cigar machine and by a pipe 39 with the suction chamber of the wrapper carrier. When a wrapper covers the suction holes in the bottom of the head H of the carrier, the suction in chamber 37 is strong enough to pull down piston 36 and thus to unlatch one side of collar 29 as shown in Fig. 1. But when the suction holes of carrier

head H are open through the failure of a proper wrapper pick-up, most of the suction in pipe 38 is spent through pipe 39, leaving in chamber 37 an amount insufficient to depress lever 301.

Therefore, where no wrapper is present on the wrapper carrier head, no paste will be forced from the applicator 45 because plunger 15 will be locked in inoperative position by latch 301.

The action of cam lever 25, at the proper moment, causes the arm 17 to be pulled into position 17' in which a pin 40 carried between its fork ends, engages a nose 41 at the end of latch lever 31, thereby depressing it, as shown in dotted lines, and frees the collar 29, provided the lever 301 is held down by suction on piston 36. The spring 30 then pushes the plunger 15 against the fork ends of arm 17, thereby forcing a given quantity of paste into the outlet 21 of the reservoir. With this arrangement, the plunger 15 remains at rest until the arm 17 has reached the end of its stroke, and then advances in one quick jump. However, the latch lever 31 and the tripping pin 40 may be omitted, in which case, when lever 301 is unlatched, the plunger 15 immediately follows the movement of arm 17, thus delivering the paste in a more gradual manner, which is preferred in applying paste to the wrapper.

This modified form of the invention is shown in Figs. 12-15 and is similar to the invention shown in Figs. 1 and 2 except that members 31, 40 and 41 have been omitted therefrom. Members 401, 412—415, 417—430, 432—439, 442—452, 454, 456—458, 462, 463 and 463a perform operations which are similar to those performed by the corresponding elements shown in Figs. 1 and 2 and for this reason a more detailed explanation is deemed unnecessary since such explanation has already been given in connection with Figs. 1 and 2.

A conventional cam device, which will give a simple reciprocating movement during each machine cycle (such as the type shown in the Belot Patent No. 1,128,093), is provided for actuating the lever arm 417. A detailed view of such conventional cam device is shown in Figs. 12 and 13.

A conventional cam 496 having a single indented portion 497 is mounted on a shaft 498 of the cigar machine and makes one complete revolution for each cycle of the cigar machine. A cam follower 495 mounted on the spring tensioned arm 425 is held against the cam by means of spring 426. The arm 425 is pivotally mounted at one end to the support 413; and the other end, by means of a ball and socket joint 424, imparts a simple reciprocatory movement to the rod 423 during each cycle of the cigar machine. The rod 423 in turn, also by means of a ball and socket joint 422, imparts a simple to-and-fro movement to lever 417 during each cycle of the cigar machine.

When the suction holes of the carrier head H are closed by means of a wrapper being carried thereby, sufficient suction is created to cause the lever 401 to be unlatched; whereupon the collar 429, fixedly mounted on plunger 415, immediately follows, under the pushing action of spring 430, the withdrawing movement of arm 417. The displacement of the paste is in this manner always under control. As already mentioned, the rate at which the lever 417 travels is controlled by means of the cam device shown in Figs. 12 and 13. Such a controlled displacement of paste is particularly desirable where paste is being applied to a wrapper in order to

avoid unnecessary splashing which otherwise might cause discoloration of a wrapper.

From outlet 21, the paste passes through a demountable pipe-elbow 42 and a connecting pipe 43 into a T 44 from which it enters the delivery member 45. The elbow 42 is held in the reservoir outlet by a spring-tensioned ball 46 engaging with a V-groove in the shank of the elbow, so that it can readily be demounted by an upward pull. The elbow 42 communicates with outlet 21 by a horizontal inlet opening 47, see Figs. 4 and 5. By releasing the clamp screw 48, the pipe 43 can be withdrawn from elbow 42. The T 44 is loosely mounted on a collared stud 49 clamped in a slotted bracket 50 supported on a post 51 attached to bedplate 13, the flexible nature of this arrangement facilitating the convenient adjustment of the position of the paste-delivering member 45. It will be obvious that the construction and arrangement of the parts of this device are such that they can be assembled or taken apart with great rapidity and that it is a relatively simple matter to clean them if paste handled therein should tend to congeal and clog the line.

In the T 44, Figs. 1, 6 and 7, is clamped a pipe 52 communicating by an opening 53 (Fig. 9) with pipe 43, and on pipe 52 is slidably mounted a sleeve 54 closed by a spring-tension valve 55 in a nozzle 56. To pipe 54 is clamped a collar 57. Figs. 6 and 7, connected with T 44 by a spring 58, the said collar being slidable on a guide pin 59 carried by a lug of T 44. To the nozzle 56 is attached the paste delivery member, Figs. 8 and 9, consisting of a closed, elongated delivery element 45 shaped to conform to the configuration of the flag of the wrapper, and provided with a plurality of openings 61 along its surface through which paste is expelled for application to a wrapper. A plurality of ducts 60 conduct the paste from nozzle 56 into the applying head 45. The paste forced by the plunger 15 into the elbow 42, on entering the already filled pipe 52 raises sleeve 54 which is vertically slidable on pipe 52 upward against the pressure of spring 58, which normally maintains sleeve 54 correctly positioned on pipe 52. Delivery head 45 is raised in this manner hydraulically until it contacts with a wrapper on carrier head H. When the upward movement of head 45 has been checked by engagement with a wrapper positioned upon the carrier head, the continued pressure of the paste exerted upon valve 55 causes spring 550 to be compressed, whereupon the valve opens and paste is extruded from the nozzle 56 into the paste delivery head 45 thereby adding to the supply of paste in the applying head 45, and paste is forced through the openings 61 of head 45 on to the wrapper. Valve 55 is arranged with its stem portion projecting into the paste line. (See Fig. 9.) By means of this construction, paste will not be allowed to dry on or clog the valve stem of the paste line and the valve operating mechanism. Consequently, this structure is rendered more efficient than any similar device heretofore known. If desired, openings 61 located a distance from ducts 60, may be formed larger in diameter than those directly adjacent thereto which allows for a more equal distribution of the paste extruded from member 45.

In order to fill the entire paste-carrying system before starting the operation of the cigar machine, a small priming pump 62 is mounted in an opening provided for this purpose on top of the paste reservoir 14. The pump is screwed

tightly in its sockets in the reservoir (Fig. 1) when paste is to be forced by air pressure into the paste line. After paste feed has started, the pump is unscrewed and the entrapped air is allowed to escape through port 63, which allows the port 63a formed in the reservoir casting to come into communication with port 63 in the pump.

In the binder paster, Figs. 10 and 11, the operating arm 117 is actuated by a vertical rod 64 controlled by a cam of the cigar machine (not shown). As in the wrapper paster, paste forced by a plunger 115 into the outlet 121 of a reservoir 114, enters through an opening 65 into the vertical shank of a pipe elbow 66 which in this case is swingably inserted into bushings 67 in the outlet of reservoir 114 and at its lower end carries a fixed collar 68. A pipe 69 clamped into elbow 66 carries the paste to the delivery nozzle 70 from which it is squirted through holes in a cap 71 upon the binder leaf held on the rolling apron A of the cigar machine upon having been brought into position by the action of operating arm 117. A spring-tensioned valve 90 is inserted into nozzle 70 to obviate eventual dripping of paste on the cessation of the forward stroke of plunger 115, and to prevent air from sucking in on its return stroke. The valve construction and its operation is similar to that described in connection with nozzle 56 of the wrapper paste applier.

On the shaft 16 is fixedly mounted a gear segment 72 meshing with a bevel gear 73 loose on a horizontal shaft 74 turning in a bushing 75 fast in housing 76 which is similar to housing 12 of Fig. 1. From gear 73 projects an axial pin 77 against which bear strong springs 78 adjustably supported in a collar 79 fast on shaft 74. Shaft 74 has a bevel gear 80 in mesh with a bevel gear 81 on a vertical shaft 82 turning in housing 76 and having a fixed collar 83 carrying an adjustable stop screw 84 engaging with a pin 85 in housing 76 when the nozzle 70 is in delivery position. A vertical pin 86 in collar 83 engages with a slot in collar 68, thereby transmitting the motion of shaft 82 to elbow 66 and to the swinging arm 69. The swing of arm 69 having been adjusted by stop screw 84, any excess motion of arm 72 is absorbed by the springs 78 in collar 79. The pin 77 and collar 79 as well as pin 83 and stop screw 84 may be omitted and the gear 73 mounted fixedly on shaft 74, in which case the angular position of arm 69 in bushings 67 must be accurately adjusted with reference to the end of the stroke of arm 72 before fastening collar 68 to it. The gears 80 and 81 are protected by a cover 87 attached to housing 76. The mechanism just described makes it very simple to remove reservoir 114 and paste applier 71 from the machine for cleaning or other purposes. In demounting the reservoir 114 it is moved to the right in Fig. 10, off bushing 91 which also performs the function of aligning the shafts 66 and 82 and the collar 68 slides out of engagement with pin 86, and leaving the paste delivering arm 69 attached to the reservoir for separate demounting, if required.

The stroke of plunger 115 in this case is adjusted by a grooved nut 88, held in place by a locking spring 89 attached to the end of the plunger. The suction pipe 138 in Fig. 10 has a branch connected to the suction chamber of the rolling apron A, so that in this case the latch lever 307 is controlled by the presence of a binder on the rolling apron and if a binder be not present no paste is fed through nozzle 90. Al-

though it is preferred to apply paste to the binder with a quick spraying action, pin 140 and latch 131 may be omitted if a gradual action of plunger 115 is preferred, in order that plunger 115 may be moved forward under action of spring 130 during forward travel of arms 117 against which collar 129, fixed to the plunger, is pressed. In applying paste to the binder, however, it is usually preferred to spray it upon the binder, and hence the latch 131 and pin 141 are both used.

It will be noted that the arrangement of parts of the improved pasting mechanism of this invention is such that the hydraulic portion thereof, that is, the paste supply with its conduits and applicator can be removed from its support and actuating mechanisms without disturbing any of the elements thereof. Referring to Figs. 1 and 10, it will be seen that paste supply tank 114 is detachably mounted upon housing 76 in which are located levers 117, 131 and 307, and also suction pump 137 and plunger 136 which controls the operation of plunger 115 reciprocable therein. Since these actuating elements are all mounted within the housing 76, it is obvious that no dust or dirt can work into this housing and accumulate on the several actuating elements above mentioned, thereby minimizing the wear and tear on these parts and the necessity for frequently cleaning them in order to maintain the paster at its greatest efficiency of operation.

The invention above described may be varied in construction within the scope of the claims for the particular device selected to illustrate the invention is but one of many possible concrete embodiments of the same. The invention is not, therefore, to be restricted to the precise details of the structure shown and described.

What is claimed is:

1. In a cigar machine, the combination with a tobacco leaf support, mechanism for applying adhesive to a leaf on said support, said mechanism comprising an adhesive applicator, a conduit, a device for feeding adhesive through said conduit to said applicator, means for locking said device against adhesive feeding movement, means for releasing said device to feed adhesive into said applicator, means for moving said device to feed said adhesive, and means cooperating with said device for controlling the speed of displacement of the adhesive by the adhesive feeding device.

2. In a cigar machine, the combination with a tobacco leaf support adapted to support a leaf section thereon, of means for feeding adhesive to a leaf section positioned on said support including a device for locking said means against feeding operation unless a leaf is positioned on said support, a suction control for said locking device constructed and arranged to unlock the same whenever a leaf is positioned to receive adhesive, a second locking member, and means for releasing said second locking member subsequent to the release of the first locking member, said releasing means being adapted to retard the operation of said adhesive-feeding means at times, and thereby to control the rate of feeding of the adhesive.

3. In a cigar machine, the combination with a support adapted to position a leaf section, of mechanism for feeding adhesive to said leaf section, comprising a pump, an adhesive applicator, a conduit connecting said pump with said applicator, a plunger in said pump arranged to

pump paste into said conduit, a latch lever adapted to prevent said plunger from feeding movement unless a leaf section is positioned on said support, means for releasing said latch lever to free said plunger for feeding movement, and means engaging said plunger to control the speed of displacement of the paste by the plunger.

4. In a cigar machine, the combination with a support adapted to position a tobacco leaf section, of mechanism for applying adhesive to a section on said support, including an adhesive feeding member, means for locking said member against feeding movement, including a pivoted latch provided with a cam portion at its free end, a control lever cooperating with said member, and means on said lever arranged to engage said cam portion and trip said latch, and means for moving said member to feed said adhesive.

5. In a cigar machine, the combination with a support adapted to position a tobacco leaf section, of mechanism for applying adhesive to a section on said support, including an adhesive feeding member, means for latching said adhesive feeding member against feeding movement, means for yieldingly holding said latching means in latching position, a reservoir cooperating with said adhesive feeding member for delivering adhesive thereto, and a priming pump connected to said reservoir for filling said adhesive applying mechanism with adhesive.

6. In a cigar machine, the combination with a support for a tobacco leaf section, of mechanism for applying adhesive to a section positioned on said support, of a yieldingly mounted reciprocating plunger, a lever adapted to retract said plunger from paste feeding position, a collar on said plunger, a spring bearing against said collar and arranged to move said plunger to feed adhesive, yieldingly mounted latch levers maintaining said plunger in retracted position, a suction control member adapted to unlatch one of said latch levers from said collar, and means carried by said first-mentioned lever for unlatching the other of said latched levers whereby said spring may displace the plunger to feed paste from said mechanism.

7. In a cigar machine, the combination with a support for a tobacco leaf section, of mechanism for applying adhesive to said section positioned on said support, of a yieldingly mounted reciprocating plunger, a lever adapted to retract said plunger from paste feeding position, a collar on said plunger, a spring bearing against said collar and arranged to move said plunger to feed adhesive, yieldingly mounted latch levers maintaining said plunger in retracted position, a suction control member adapted to unlatch one of said latch levers from said collar, means carried by said first-mentioned lever for unlatching the other of said latched levers whereby said spring may force the plunger forward to feed paste from said mechanism, and adjustable means for limiting the forward throw of said lever.

8. In a cigar machine, the combination with a tobacco leaf support, of mechanism for applying adhesive to leaves positioned on said support, a mount for said mechanism, means for detachably securing said mechanism to said mount, whereby the mechanism may be separated from the mount by a horizontal pull, said mechanism comprising an adhesive reservoir, an

adhesive applier for applying adhesive to leaves on said support, and a conduit connecting said applier and reservoir, means for detachably connecting said conduit to said reservoir, and means for releasably securing said conduit and reservoir in assembled relationship.

9. In a cigar machine, the combination with a tobacco leaf support, of a device for applying adhesive to a leaf on said support, including an adhesive applier, and hydraulically operated means for moving said applier into contact with said leaf to apply adhesive thereto.

10. In a cigar machine, the combination with a tobacco leaf support, of a device for applying adhesive to a leaf on said support, including an adhesive conduit, an applier, an adhesive reservoir, means for forcing adhesive from said reservoir through said conduit and from said applier, and means operated by the movement of said adhesive for moving said applier into contact with said leaf.

11. In an adhesive applying mechanism, means for holding an article to be coated, a source of supply of adhesive, an adhesive applier, a conduit connecting said source to said applier, a support for said applier comprising a sleeve mounting said applier, a pipe forming a continuation of said conduit, and mounting said sleeve for relative movement thereon, and means for forcing adhesive from said source through said conduit to move said sleeve relative to said pipe and thereby bring said applier into adhesive applying position.

12. In a coating device, means for holding an article to be coated, a source of supply of adhesive, an applier, a conduit connecting said applier and source, a support for said applier slideable on an end of said conduit, and means for forcing adhesive through said conduit to move said support to bring said applier into contact with said article to be coated.

13. In a coating device, the combination with an article support, of an adhesive applier comprising a nozzle, a valve mounted in said nozzle, hydraulically operated means for moving said applier into engagement with an article on said support, said means operating to open said valve and discharge adhesive from said applier at the termination of the movement of said applier into contact with an article on said support.

14. In a cigar machine adhesive applying mechanism, a reservoir for adhesive, a support for detachably mounting said reservoir, an adhesive applier, a conduit connecting said reservoir to said applier, and latching means for securing said reservoir to said support and in alignment with said conduit.

15. In a cigar machine adhesive applying mechanism, an adhesive reservoir having an outlet aperture, a support for detachably mounting said reservoir, an adhesive applier, a conduit connecting said aperture to said applier, latching means for securing said reservoir to said support, and a second latching means for securing said conduit in alignment with said aperture.

16. In a cigar machine, the combination with a tobacco leaf support, of mechanism for applying adhesive to leaves positioned on said support, comprising an adhesive reservoir, an adhesive applier, a conduit connecting said reservoir and applier, and means for releasably connecting said conduit to said reservoir for quick removal therefrom, including a conduit member provided with a shank having a reduced portion thereon, and a yieldably positioned locking device engaging said portion to hold said member coupled to said reservoir.

17. In a cigar machine, an adhesive applying device, comprising a reservoir for adhesive, a support for said reservoir, an adhesive applier, a conduit connecting said reservoir to said applier, means for detachably mounting said reservoir on said support, mechanism for controlling the feed of adhesive from said reservoir to said applier mounted wholly within said support and detachable means mounting said reservoir so constructed and arranged that said reservoir may be removed from said support without disassembling said elements.

18. In a coating device, the combination with an article support, and mechanism for applying adhesive to an article on said support, of an adhesive supply reservoir, including a conduit connecting said reservoir to said applier, a nozzle adapted to discharge adhesive into said applier, a valve forming a part of said nozzle, spring means coacting with said valve normally closing said nozzle against the passage of adhesive from said conduit into said applier, and means for forcing adhesive through said conduit to move said applier into contact with an article to be coated by movement of said adhesive, said means being effective to move said valve against the force exerted thereon by said spring thereby to open said nozzle and allow adhesive to flow from said conduit into said applier.

19. In a cigar machine adhesive applying mechanism, an adhesive reservoir, a support for said reservoir, an adhesive applier, means for detachably mounting said reservoir on said support, a conduit for conducting said adhesive from said reservoir to said applier, means for supporting one end of said conduit, a slotted collar fixed to said end of said conduit, a movable mount arranged to support said collar, a pin on said mount engaging said collar, and means for moving said mount whereby said pin will engage said slot and move said conduit and applier.

20. In a coating device, means for holding an article to be coated, a source of supply of adhesive, an applier, a conduit connecting said source to said applier, a support for said applier movably mounted on an end of said conduit, an adhesive flow control device arranged to close said conduit to prevent passage of adhesive therethrough, and means for forcing adhesive through said conduit to move said applier into contact with an article to be coated and to open said device to allow adhesive to flow through said conduit and into said applier.

HENRY H. WHEELER.
